UNITED STATES PATENT OFFICE.

HENRY G. KUCK, OF PEORIA, ILLINOIS, ASSIGNOR TO STUBER & KUCK CO., OF PEORIA, ILLINOIS, A CORPORATION OF ILLINOIS.

DISPLAY COVER FOR CONTAINERS.

Application filed November 11, 1922. Serial No. 600,299.

This invention has reference to display-covers for containers and like receptacles in which are packed and from which are dispensed cakes, crackers and similar pastry and bakery goods.

The invention has for its principal object to provide a light inexpensive display-cover adapted for detachable connection with containers of a standard type, whether 10 made of fiber-board or other non-metallic material, or of metal.

The invention comprehends a cover for containers, the opening in one side or one end of which is preferably surrounded by 15 a flange; the cover includes a flanged strip or plate to engage one edge of a container to overlie the flange disposed along one side of the opening therein and an adjacent wall, means being provided to detachably 20 attach said strip or plate to the flanged end or side of the container, and a preferably flat rectangular plate hingedly connected to said strip or plate and having a display opening covered by a transparent 25 member.

That the invention may be more fully understood, reference is had to the accompanying drawings, illustrating a preferred embodiment of the invention, in which:—

30 Figure 1 is a front elevation of my improved display-cover for containers made of metallic or non-metallic material;

Figure 2 is a side elevation looking in at the right side of Figure 1, the dotted lines 35 indicating the container;

Figure 3 is a top plan or edge view of Figure 1, the container shown in section, dotted line showing the lid swung out and away from the open end or side of a container.

40 Figure 4 is a front elevation of the open flanged end or side of a container partly broken away and in section and showing the flanged strip or plate applied thereto and with the securing means in two positions in full and dotted lines, the hinged cover or lid being removed but shown in dotted lines in open position;

Figure 5 is a detail in cross-section as the 50 same would appear, if taken on the line 5—5 Figure 4, and

Figure 6 is a perspective view partly broken away and in section showing how the strip or plate of the cover or lid is se-

cured in position to the flange at the open 55 end of the container.

Like characters of reference denote corresponding parts throughout the figures.

Containers of the type herein referred to and intended for the purposes herein stated 60 have become more or less standard, except that they are manufactured of fiber-board or other light non-metallic material and also of sheet metal. Some have removable lids or covers for the open ends or sides, 65 others have hinged lids or covers and others are furnished with other and different kinds of closures. The aim being to reduce the cost of manufacture, which ultimately reduces the cost of the products to 70 the consumer. To this end the containers are manufactured with the open ends or sides preferably surrounded by inturned flanges which not only act as a retainer for any of the different kinds of destructible closures being used, but also presents an open end or sides void of sharp edges 75 and which serves as a strengthening and stiffening means for such open end or side.

In the drawings, the container, of the 80 box like shape is designated 1 and may be made of fiber-board or other non-metallic material, or of metal. One end or one side is preferably open, as at 2 to permit of the articles being backed therein and for the removal of the same, and such opening is 85 preferably surrounded or bordered by an inwardly projecting flange 3 which may be constructed by turning in or lapping the material forming the body, as at 4, seq. 90 Figure 5. The flange 3 strengthens as well as stiffens the open end or side of the container, and eliminates sharp edges if the container is made of metal.

The display-cover includes the angular 95 strip or plate 5 and the lid or cover 6 hinged thereto. The construction of such display-cover and its manner of attachment permits it to be interchangeably attached to the open end or side of a container so 100 as to be swung in different directions. In this way, the dealer may attach a display-cover to a container so that the lid 6 may be swung up or from either side, as he may desire.

The strip or plate 5 is attachable to one 105 edge of the container, adjoining one strip of the flange 3 and one side wall of the con-

tainer, see Figures 4, 5 and 6. This gives a bearing and purchase of the strip on the edge of the container. The ends of that portion of the strip 5 overlying the flange 3 are spread as at 7 so as to overlie a triangular part of the opening 2, and pivotally connected to the underside of said spread ends 7 are clasps or hooks 8 which may be swung to engage the underside of the flange 3, see Figures 4, 5 and 6 so as to detachably secure the strip or plate 5 to the container, and thus attach the lid or cover 6 in position, also preventing the strip or plate 5 from flipping off when the lid or cover 6 is swung open. Also that portion of the strip 5 overlying the flange 3, between the spread ends 7 is bent inwardly at right angles, as at 9, see Figures 5 and 6 which bears against the edge of the flange 3 of the container and serves as an additional seating and retaining means for the strip or plate 5 on the container. To the upper or horizontal portion of the strip or plate 5 are connected a pair of spaced hinge members 10 and to said hinge members is connected a rod 11 on the lid or cover 6, the latter being cut out or away, as at 12 to provide seats for the members 10, see Figure 1.

The lid or cover 6 is preferably a flat rectangular plate, of a size, together with the strip or plate 5 to cover the open end or side 2 of the container, see Figures 1 and 3. It is provided with an enlarged display opening 13 covered by a transparent member 14, such as glass, which may be held thereon in any suitable manner, such as by flanges 15 formed by turning in the edges of the plate, or which may be soldered or secured to the plate in any suitable manner. The flanges 15 may be so disposed, see Figure 3 that when the lid or cover 6 is closed, said flanges lie within the opening 2 of the container and adjacent the inner edges of the flanges 3 and position the lid or cover securely over the opening 2 in the container.

What I claim is:—

1. A display-cover for containers, including in combination, a substantially flat rectangular lid arranged to cover the entire openside of a container and having a display opening, a transparent covering for said opening, a narrow strip having spread ends, means hingedly connecting said lid to said strip, and securing members pivotally connected to the underside of the spread ends of said strip arranged for removably connecting said strip and lid to a container.

2. A display-cover for containers, including in combination, a substantially flat rectangular lid arranged to cover the entire openside of a container and having a dis-

play opening, a transparent covering for said opening, a narrow strip having angular portions to overlie a part of one end and a side of a container and provided with an inwardly extending flange along one edge, means hingedly connecting said lid to said strip, and a pair of securing members pivotally connected to said strip arranged for removably connecting said strip and lid to a container.

3. A display-cover for containers, including in combination, a substantially flat lid arranged to cover the entire openside of a container and having a display opening, flanges surrounding said opening, a transparent member covering said opening and held by said flanges, a narrow strip having spread ends, means hingedly connecting said lid to said strip, and means pivoted to the underside and at the spread ends of said strip for removably attaching the strip and lid to a container.

4. In combination with a container, having an openside bordered by an inwardly extended flange, of a display-cover comprising two members, one a substantially flat lid arranged to cover the entire openside of said container and having an opening, a transparent covering for said opening; the other a narrow strip with spread ends having a hinged relation with said lid and having a portion to overlie said flange, and engage an outside wall of said container, and pivoted clasps on the inside of said strip and at the opposite spread end thereof arranged to be swung into engaging position on the underside of said flange for detachably attaching said lid and strip to said container.

5. In combination with a container having an openside bordered by an inwardly extended flange, of a display-cover comprising two members hingedly connected, one a substantially flat lid arranged to cover the entire openside of said container and having an opening, a transparent covering for said opening; the other a narrow angular strip, one part of which overlies a part of said bordering flange and provided with an inside flange engaging the edge of the bordering flange, and the other part of which has a bearing against an adjacent outside wall of said container, and a pair of clasps pivotally connected to the inside of said angular strip and adapted to be swung into securing position against the under side of said bordering flange for detachably attaching said lid and strip to said container.

In witness whereof I have hereunto affixed my hand this 7th day of November, 1922.

HENRY G. KUCK.
